UNITED STATES PATENT OFFICE.

FRITZ KIESLER, OF BERLIN-CHARLOTTENBURG, GERMANY, ASSIGNOR TO SIEMENS-SCHUCKERTWERKE, G. M. B. H., OF BERLIN, GERMANY, A CORPORATION OF GERMANY.

MOTOR ARC-LAMP.

1,205,750.

Specification of Letters Patent.

Patented Nov. 21, 1916.

Application filed April 17, 1914. Serial No. 832,664.

To all whom it may concern:

Be it known that I, FRITZ KIESLER, a German citizen, and resident of Berlin-Charlottenburg, Germany, have invented 5 certain new and useful Improvements in Motor Arc-Lamps, of which the following is a specification.

This invention relates to motor arc lamps and comprises an improved construction for 10 such lamps, whereby the ignition will be essentially facilitated in case scoria has been deposited on the points of the carbon pencils.

In arc lamps frequently it is found that 15 the carbons are prevented from forming a proper conductive contact, thereby preventing ignition on account of the insulating deposit or layer of scoria on the ends of the carbons.

20 My present invention is designed to obviate this defect and consists essentially in providing means for setting said carbons in a hammering motion in case ignition should not immediately take place in order to thus 25 break the layer of scoria and to initiate the ignition.

More particularly my invention consists 30 in an especial kind of locking device used ordinarily in motor arc lamps between the driving works and the carrying disk for the movable carbon. This locking device ordinarily serves only to enable the carbon 35 holders to be moved apart for trimming the lamp without setting the driving works in motion.

My invention will be more fully understood by reference to the accompanying drawings, of which—

Figure 1 is a cross-section and Fig. 2 a 40 front view of an arc lamp according to my invention. Fig. 3 represents in diagram a motor drive as applied to the arc lamp according to my invention.

In the drawings I have shown a mode of 45 construction for a motor lamp with carbons which are arranged oppositely to each other. The last wheel *a* is assumed to be connected with the driving works as to tend to move in counter-clockwise direction 50 (Fig. 2) and carries the pawl *b* having a well rounded nose and the spring *f* for the pawl. The locking wheel proper, which couples the rope wheel and chain wheel with the driving mechanism, is of a special form 55 and rigidly connected with the rope wheel

and chain wheel *c*. It consists essentially of two parallel disks *d*₁ and *d*₂ between which a circular series of easily rotatable rollers *e* are mounted which rollers form so to say the locking teeth and which must be of sufficient size to permit pawl *f* to ride over them when disks *d*₁, *d*₂ are arrested. This locking device may easily be so constructed that the force required to cause pawl *f* to ride over rollers *e* is smaller than that which can be exerted by the driving works at the normal lamp voltage.

The operation of the aforescribed apparatus will be as follows: If the arc lamp be switched in, the driving works will be 70 so driven that the last wheel *a* in Fig. 2 will be rotated in a counter-clockwise sense. The pawl *b* will then first positively carry the locking wheel with it and move the carbons toward each other until they will contact, 75 whereupon the locking wheel cannot be moved farther. If now an ignition does not immediately take place, the power of the driving works will continue to rotate wheel *a* in the same direction so that the pawl 80 will slide over a roller of the locking wheel toward the next roller and will thereby give a short impact to the locking wheel for rotation in a clockwise sense each time the pawl passes a roller, whereby the carbons 85 will be caused to hammer upon each other. Immediately or after a few repeated hammering motions the points of the carbons will break through the insulating layer and properly form a conductive contact with 90 each other.

In Fig. 3 the motor drive is represented as comprising the frame 10 upon which is suitably mounted the field structure 11 for rotating an armature disk 12. The armature disk 12 is journaled in brackets such as shown at 13, and its shaft bears a pinion 14 which meshes with a gear 15, the latter bearing a pinion 16 meshing with a gear *a* corresponding in all respects with that illustrated in Figs. 1 and 2.

I claim:

In a motor arc lamp the combination of 105 driving works, a supporting disk for the movable carbons, a locking mechanism between said driving works and said supporting disk, rollers mounted upon said locking mechanism for temporarily releasing the connection between driving works and supporting disk which connection is effected by 110

said locking mechanism in case of non-ignition of the lamp, said locking mechanism comprising a locking pawl and a locking wheel, said rollers being adapted to impart to said locking wheel an impact for backward motion, whereby the carbons will be set in motion to hammer upon one another.

In testimony whereof I have hereunto set my signature in the presence of a subscribing witness.

FRITZ KIESLER.
